CLARENCE R. HILL, OF MUSKEGON, MICHIGAN

DOOR OPERATING DEVICE

Application filed October 28, 1930. Serial No. 491,710.

My invention relates generally to door opening and closing devices and more particularly to a spring closure apparatus or mechanism adapted to be applied to the inner side of inwardly swinging garage doors whereby they may be quickly and expediently opened and closed and held in either position by the closing and opening manipulation.

10 The present invention is an improvement or modification over the door operating device as embodied in my application filed September 29, 1930, Serial No. 484,982, the previously filed case dealing with doors 15 which swing outwardly and the present case being concerned with doors which swing inwardly. Obviously, both types of construction have their particular uses, but the inwardly swinging doors are extremely desirable in the colder climates because snowfall hinders and oftentimes prevents the opening of outwardly swinging doors.

One aim of the present invention is to create a relatively simple structure which will 25 be easy to install and which will function in an efficient manner and which will maintain the doors either in fully open or closed position, as desired.

Another aim or object is to so arrange the 30 tensioning springs as to make them serve two purposes, i. e. maintain the door in closed position or maintain the door in open position.

Still further objects or advantages subsidiary or incidental to the aforesaid objects, or resulting from the construction or operation of the invention as it may be carried into effect, will become apparent as the said invention is hereinafter further disclosed.

40 In the drawing:—

Fig. 1 shows a plan view, partly in section, illustrating my improved door operating device as applied to a garage and showing the doors in open, closed and intermediate positions, and

45 Fig. 2 is a sectional view taken along the plane of line 2—2 of Fig. 1.

Similar numerals represent similar parts throughout the two figures.

50 The invention is shown in connection with

a building such as a garage, having spaced vertical sides 2 with an open front adapted to be closed by hingedly mounted doors 3, 4 and 5, the doors 4 and 5 being pivotally connected together. Doors 3 and 5 are adapted to 55 swing inwardly and the auxiliary door 4 is adapted to be received against the outer face of the door 5 as clearly shown in the dotted line construction of Fig. 1.

A bracket member 6 is fixed to the vertical 60 edge of the door 3 and the link member 7, consisting of two spaced bars, see Fig. 2, is pivotally connected thereto. The free end of the link 7 is pivoted to the arm or rod 8, this rod being pivotally mounted at 9 upon 65 the depending frame member 10, rigid with the garage or building, and a spring 11 is fastened to the arm 8 as shown, the other end of the spring being attached to the frame 10. The spring 11 tends to pull the arm 8 toward 70 the door 3 and acting through the member 7 holds the door in its closed position.

A rope or flexible element 12 is fastened to the rod 8, extends around the pulleys or sheaves 13 and leads to a point exterior of the 75 building, thus allowing manipulation of the doors from a point outside of the garage. The auxiliary door 4 has a bracket 16 attached thereto and a link 17 extends inwardly as shown, this link being pivotally attached to the rod or arm 18, the member 18 being pivotally attached to the frame member 10, as at 19.

A tension spring 21, similar to the tension spring 11, acts upon the link 18 and a flexible element 22 extends around 80 pulleys 23 to any desired point within the garage. The ropes or flexible elements 12 and 22 are connected together as at 30.

85 The connection just recited makes it possible for operation of the doors to be controlled from either inside or outside of the garage. The person desiring to open the doors grasps either of the ropes and gives the same a short pull thus pulling the arms 8 and 18 inwardly against the actions of the springs 11 and 21, respectively. The links 7 and 17 also travel inwardly and cause the doors 3, 4 and 5 to be drawn inwardly. The free edge of the auxiliary door 4 is guided in a track or the like in the ordinary manner, as is well 95 100

known to those skilled in this art, and hence it travels to the central position and likewise the door 3 travels to a mid position. However, the inertia of the doors causes them to swing past the dead center point and thereupon the arms 8 and 18 commence to return to their original position, this motion being augmented by the springs 11 and 21.

10 The springs continue to act until the doors are positioned adjacent to either side of the garage as clearly shown in Fig. 1. When it is desired to close the doors the flexible elements are again pulled and the reverse operation takes place.

15 It has been determined that the momentum of the swinging doors will carry them through a considerable portion of the middle part of their travel. This is particularly true because of the position of the spring at 20 this point which is acting largely against the pivot of the arm 18 and therefore exerts comparatively small effort. It is therefore only necessary to pull sufficiently on the operating rope 12 (or 22) to start the doors from 25 either closed or open position and to give them sufficient momentum to carry them past mid-position after which the action of the springs will complete the movement.

30 While I have described a complete embodiment of my invention I do not wish to be limited to the particular construction shown, my invention being in fact limited solely by the attached claims.

35 I claim:

1. The combination with a hinged door of means for opening or closing said door comprising, a swinging arm, means connecting a swinging portion of said arm with a swinging portion of said door and spring means connected with said arm whereby the spring means will be tensioned during the first part of the movement of the door in either an opening or closing direction and said spring means will act upon said arm to complete the swinging movement of the door in either of said directions, said arm being adapted to lie in substantially the same position regardless of whether the door is in a fully opened or a fully closed position.

50 2. In a swinging door having an auxiliary door adapted to fold thereagainst, said auxiliary door having its free edge guided, the combination of a bracket fixed to the auxiliary door near its hinged edge, a link extending laterally from the door and being pivoted to the bracket, an arm pivoted to the opposite end of the link, means for pivotally mounting the other end of the arm, spring means acting upon said arm to maintain the doors in either a closed or open position, a third door juxtaposed with its free edge adjacent the free edge of the auxiliary door, a second link pivoted to the third door adjacent its free edge, a second arm

pivoted to the link, means for pivotally mounting the other end of the second arm, spring means for acting upon the second arm to maintain the door closed and manual means cooperably associated with the arms 70 to open or close the doors simultaneously.

3. In a building having an entrance opening, the combination of, two swinging doors pivotally mounted at either side of the opening and adapted to swing into the plane of 75 the opening, a frame, two arms pivotally attached to the frame, two links pivotally attached to the free edges of the doors, means for pivotally connecting the free ends of 80 each set of links and arms, spring means acting upon said arms tending to operate the said doors, individual flexible means leading from each of the arms for the purpose described, means for guiding the two flexible means in parallelism a short distance, and means for connecting the said parallel portions of the said flexible means together for 85 the purpose described.

In testimony whereof I affix my signature. 90
